UNITED STATES PATENT OFFICE.

WILLIAM F. GEHRIG, OF NEWARK, NEW JERSEY, ASSIGNOR TO ESSEX SPECIALTY CO., INC., OF BERKELEY HEIGHTS, NEW JERSEY, A CORPORATION OF NEW JERSEY.

MACHINE ELEMENT.

Application filed May 25, 1922. Serial No. 563,733.

To all whom it may concern:

Be it known that I, WILLIAM F. GEHRIG, a citizen of the United States, residing at Newark, in the county of Essex and State of New Jersey, have invented certain new and useful Improvements in Machine Elements; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in machine elements; and the invention has reference, more particularly, to a novel construction of universal fulcrum or pivotal support and combined self-clamping lock for adjustably pivoting and supporting rectilinear rods for various mechanical purposes.

The invention has for its principal object to provide a novel construction of universal self-clamping support for adjustably mounting a rod or the like, so that the latter is capable of a four-fold movement, viz, oscillatory or pivotal movement in a horizontal plane, oscillatory or pivotal movement in a vertical plane, longitudinal movement in either direction, and rotary movement about its longitudinal axis in either direction.

Other objects of this invention, not at this time more particularly enumerated, will be clearly understood from the following detailed description of the same.

With the various objects of this invention in view, the same consists, primarily, in the novel arrangements and combinations of the various devices and parts, as well as in the details of the construction thereof, all of which will be hereinafter more fully described and claimed.

The invention is clearly illustrated in the accompanying drawings, in which:—

Figure 1 is a side elevation, with a part of the mounting broken away to show the means for supporting the rod; Figure 2 is a plan or top view; Figure 3 is a transverse vertical section, taken on line 3—3 in Figure 2; and Figure 4 is a detail transverse section through the rod and hemispherical clamping members, the latter being in position to be assembled with the former.

Similar characters of reference are em-

ployed in all of the hereinabove described views, to indicate corresponding parts.

Referring now to said drawings, the reference character 1 indicates any suitable base or foundation upon which the support is fixed. Secured upon said base 1, by screws 2, or by any other suitable fastening means, or in any other suitable manner, is a bearing standard, clip or bracket having a bottom portion 3 resting upon the base 1, and through which the fastening screws 2 pass. Connected with said bottom portion 3, at the sides of the latter and preferably as integral parts thereof, are a pair of upwardly extending standard members 4, which are laterally spaced apart and opposed one to the other. Said bearing standard, clip or bracket is preferably made of sheet metal, of such qualities that said standard members 4 are possessed of a requisite degree of springiness or resiliency. Normally said standard members 4 are inclined toward or converge somewhat toward each other, as indicated by the dotted position of the same shown in Figure 3, so that when moved apart, they will be placed under a tension tending to move the same toward each other, and thereby will grip and exert pressure upon any element supported between the same under such conditions. Said standard members 4 are provided, adjacent to their upper free ends with circular bearing openings or seats 5 which are transversely alined one with the other. Interposed between said standard members, so as to be engaged thereby and seated movably relative to said bearing openings or seats 5, is a split spherical carrier consisting of two, preferably separate, substantially hemispherical members 6 and 7 having their rounded outer faces respectively seated or journaled in the respective bearing openings or seats 5 of said standard members. Said hemispherical members 6 and 7 are preferably hollow (although it is not absolutely essential that they should be), and their opposed sides or inner faces are provided with indentations or notches 8 diametrically aligned so as to form seats or guideways to straddle and engage a straight rod 9 or similar element, which is interposed between said hemispherical members 6 and 7 so as to be supported thereby in diametrical extension therebetween in such manner as to be capable of a longitudinal adjusting

movement and also an axial rotary adjusting movement relative thereto.

It will be noted from an inspection of the drawings, that said carrier rod 9, by reason of the novel mounting of the same, is capable of a substantially universal adjustment, whereby the same may be disposed in a great variety of positions. The adjustable movements thus rendered possible to the rod 9 are four-fold, viz, oscillatory or pivotal movement in a vertical plane (as indicated by dotted lines in Figure 1); oscillatory or pivotal movement in a horizontal plane (as indicated by dotted lines in Figure 2); longitudinal movement in either direction; and rotary movement about its longitudinal axis in either direction. Owing to the fact that said resilient or spring-like standards 4 are placed under tension when the parts are assembled, it follows that the hemispherical members 6 and 7 will be pressed toward each other, thereby frictionally engaging and gripping the rod 9 supported intermediate the same, so that oscillatory movements, 25 in either horizontal or vertical planes, which are imparted to said rod 9 will be transmitted to said hemispherical members 6 and 7, which will consequently pivot or fulcrum such movements by reason of the rotation of 30 the members 6 and 7 in the bearing openings or seats 5 of the standard members 4, without danger of disengaging the rod itself from its operative assembled relation as disposed between said hemispherical members. 35 To move the rod longitudinally, or to rotate the same on its longitudinal axis, sufficient force, properly directed, is applied to the rod to overcome the frictional grip of said hemispherical members, so that the rod will 40 slide or rotate relative to the seats or notches 8.

While the supporting means for mounting the rod will thus readily admit of a desired range of four-fold adjusting movements, as described, said means by reason of its character and construction, provides a very important additional function, viz, that the rod 9 will be frictionally gripped and clamped or held stationary in any position to which it has been adjusted, and will thus maintain its adjusted position.

This functioning is due to the fact that the spring-like standard members 4 bear frictionally and tensionally against the hemispherical members 6 and 7, and in turn force the latter into frictional binding engagement with the rod 9, and consequently such frictional resistances thus established,

tend, first to bind or hold the hemispherical members 6 and 7 against free rotation relative to the bearing openings or seats 5 of the standards 4, and, second, tend to bind or hold the rod 9 against free longitudinal or rotative movement relative to said hemispherical members; such movements being possible only when a proper manipulative force sufficient to overcome such resistances is applied. 60 65

I am aware that some changes may be made in the various arrangements and combinations of the devices and parts, as well as in the details of the construction of the same, without departing from the scope of this invention as set forth in the foregoing specification, and as defined in the appended 70 75 claims. Hence, I do not limit my invention to the exact arrangements and combinations of the various devices and parts as described in said specification, nor do I confine myself to the exact details of the construction 80 of said parts as illustrated in the accompanying drawings. 85

I claim:—

1. In a device of the kind described, a pair of opposed resilient standards having a bearing openings, a split spherical body disposed intermediate said standards with its opposite convex surfaces rotatably journaled in said bearing openings, and a rod extending diametrically through said split spherical body so as to be frictionally engaged thereby but movable relative thereto, the tension of said standards upon said split spherical body tending to constantly thrust the members of the latter into frictional binding relation to said rod. 90 95

2. In a device of the kind described, a pair of opposed standards having bearing openings, a pair of hemispherical members intermediate said standards having their convex faces seated respectively in said bearing openings, said standards being under spring tension tending to constantly press said hemispherical members together, said hemispherical members having aligned diametrically disposed seats at their opposed faces, and a rod extending between said hemispherical members and frictionally engaged by the seats thereof. 100 105

In testimony that I claim the invention set forth above I have hereunto set my hand this 11th day of May, 1922.

WILLIAM F. GEHRIG.
